UNITED STATES PATENT OFFICE.

CHARLES W. E. CLARKE, OF NEW YORK, N. Y.

BLOWER SYSTEM.

1,137,463.

Specification of Letters Patent. Patented Apr. 27, 1915.

Application filed October 23, 1909. Serial No. 524,102.

To all whom it may concern:

Be it known that I, CHARLES W. E. CLARKE, a citizen of the United States, residing in the city, county, and State of New York, have made a certain new and useful Invention in Blower Systems, of which the following is a specification.

This invention relates to blower systems, and particularly to such systems as applied to locomotive round houses, sheds or the like.

The object of the invention is to provide a blower system wherein the locomotive fire box or furnace chamber may be placed under the influence of an induced draft to facilitate and hasten the firing up of the locomotive.

A further object is to provide a blower system with means for absorbing the heat from the heated medium, gases or other products of combustion drawn from a locomotive or other source.

A further object is to provide means for automatically regulating and controlling the supply of the heating medium and to utilize the medium heated thereby.

Other objects of the invention will appear more fully hereinafter.

The invention consists substantially in the construction, combination, location and relative arrangement of parts all as will be more fully hereinafter set forth, as shown in the accompanying drawings, and finally pointed out in the appended claim.

Referring to the accompanying drawings and to the various views and reference signs appearing thereon, Figure 1 is a view in elevation somewhat diagrammatic of a blower system embodying my invention, showing the application of the same to a locomotive. Fig. 2 is a top plan view of the same, the locomotive being omitted and a part of the automatic regulating means in section. Fig. 3 is a broken detail view of a portion of the blower system parts broken out and parts in section, showing an economizer, or heat absorbing device employed in connection with the principles of my invention. Figs. 4 and 5, are broken detail views, in section of parts of the automatic controlling means.

The same part is designated by the same reference sign wherever it occurs throughout the several views.

When locomotives arrive at a terminal station it is customary to draw off the steam from the boilers thereof, and, oftentimes, to

draw off the heated water from the boiler, 55 and also to draw off the heat from the firebox or furnace chamber, for the purpose of cleaning out the locomotive and supplying its boiler with fresh water and its furnace chamber with a fresh fire-bed. The heat 60 from the fire box is ordinarily carried off to the atmosphere through the smoke stack of the round house or shed, or otherwise, and is consequently wasted. Moreover, in starting up the fire in the fire box, or in filling 65 the locomotive boiler with fresh water, it has been a common practice to employ a cold air draft in the one case and cold fresh water in the other, with the result that the firing 70 up operation is retarded, and the steam generation is delayed.

It is among the special objects of my present invention to provide a blower system in which is employed an economizer arranged to absorb the heat from the fire box products 75 or other source and to apply the absorbed heat to a medium, such as air or water, which can be utilized for any purpose for which such heated medium is adapted, such for instance, as for heating the round house 80 or shed, for supplying the boiler of the locomotive initially with heated fresh feed water, where water is the medium heated, or for supplying a draft of heated air, where air is the medium heated, to the fire box of 85 the locomotive in starting up the fire therein, thereby facilitating and expediting the operation of firing or if getting up steam, economizing in time and in fuel and saving 90 and turning to useful account what has been before wasted and lost. These objects and purposes, and others analogous thereto, may be carried out in a wide variety of ways and by means of a wide variety of different arrangements. While, therefore, I have 95 shown, and will now describe a form and arrangement of devices which I have found to be efficient for the purpose, my invention in its broadest scope, as defined in the claim, is not to be limited or restricted to the specific arrangement of details shown.

In the drawings, reference sign A, designates a smokestack or chimney of, for instance, a locomotive round house, or other convenient place, and which communicates 105 with a main line of piping B, in which is located a blower fan C, or other suitable draft inducing device. Communicating with the

main pipe line are a plurality of extensions D, each adapted to be brought into register or other convenient communication with the smokestack of a locomotive as shown at E. Located in the line of the main pipe line is an economizer F, which may be of any suitable, convenient or desired construction, and through which is to be circulated a suitable heat absorbing medium, such as water or air, the heated products forced through the main pipe line circulating around and about the piping of the economizer. In the arrangement shown, water is circulated through the economizer and absorbs the heat from the heated products drawn from the locomotive firebox, or other source, the heated water being delivered from the economizer F, through any suitable connection pipe G, or to a heating coil T, or other point where the heated medium is to be utilized.

It may sometimes be desirable to automatically control and regulate the amount of the heated gases or other products to be circulated through the main pipe line and the economizer. I propose to accomplish this result from the heated products themselves. To this end I employ an auxiliary connection H, from any desired source of heat such as the smoke flue of the usual plant furnace or other source and leading to the main pipe line. In this auxiliary connection I place a damper J, and I provide means controlled by the heated products in the main pipe line system for automatically operating the damper J, according to the requirements, whereby more or less of the heated products may be circulated around the economizer. Thus in case the heated products from the fire box of a locomotive are not sufficient to attain the degree of heat in the economizer the deficiency can be made up from the flues. A simple arrangement of means for effecting the automatic regulation referred to is shown wherein a cylinder K, is provided with a piston, the rod L, of which is connected to a crank arm M, mounted on the shaft which carries the damper J. Pressure medium is supplied to one end of cylinder K, from any convenient source through pipe N, in which is located a valve for controlling the supply of pressure medium to the cylinder K. This valve is arranged to be operated thermostatically by the heat passing through the main pipe system B. Thus, I have shown a device P, see Fig. 4, extending into the pipe B, and also into the casing R of the valve. This device may be of suitable metal or other material influenced by the heat to which it is subjected whereby according as the heat increases or decreases the said device expands or contracts and by the expansion or contraction of the same effects the proper operation of the valve, thereby permitting a greater or less amount of pres-

sure medium to be admitted to cylinder K, thereby, through the resulting operation of the piston therein, and its connections to valve J, permitting a greater or less amount of the heating medium to be drawn from the flue S, and circulated around the economizer as may be desired.

While I have shown one specific arrangement of thermostatic control it is obvious that my invention in the broad scope thereof and as defined in the claim is in no wise to be limited or restricted to the exact details thereof.

The operation of the apparatus is very simple and can be readily comprehended.

When a locomotive arrives at the round house after completing a run, for the purpose of being cleaned out and put in condition for the next run, an extension D of the pipe line system is coupled to the locomotive smoke stack, and the heated products from the fire box are drawn off through the pipe system. Instead of delivering these heated products to the power or round house chimney or smoke stack, they are caused to first travel through the economizer through which is circulated a heat absorbing medium, such as air or water, and which absorbs the heat from the heated products, and is thereby enabled to save such heat and apply the same to useful purposes such as heating the building by coil as T, or heating the fresh feed water to be supplied to the boiler, or for any other purpose for which it is adapted. In this manner the boiler and the fire box of the locomotive are cleaned out and made ready to receive the fresh supply of clean feedwater, and a fresh fuel bed is built up in the furnace fire box, and, if desired, in firing the fresh bed of fuel the heated air, if air is the heat absorbing medium employed, may be drawn through the fire box by reason of the connection of the pipe system with the locomotive smokestack, thereby utilizing heated air instead of cold air for draft purposes in the fire box, and hence greatly facilitating and hastening the firing operation.

Having now set forth the object and nature of my invention, and a construction and arrangement embodying the principles thereof, what I claim as new and useful and of my own invention, and desire to secure by Letters Patent is:

The combination with a chimney and a locomotive having a smoke stack, of a main pipe line delivering at one end to the chimney and having a plurality of detachable connections at its other end each adapted to be connected to a locomotive smoke stack, an economizer and a blower located in said main pipe line, means for circulating water through said economizer, an auxiliary pipe line connection communicating with an independent source of heat and delivering to

the main pipe line, a thermostatic means for automatically controlling the delivery of heat medium through said auxiliary pipe line, and means for utilizing the heated water from the economizer.

5 In testimony whereof I have hereunto set my hand in the presence of the subscribing

witnesses, on this 16th day of October, A. D., 1909.

CHARLES W. E. CLARKE.
